UNITED STATES PATENT OFFICE.

WADE H. HILLHOUSE, OF LEBANON, GEORGIA.

CROSSING SIGNAL.

Application filed April 7, 1924. Serial No. 704,781.

To all whom it may concern:

Be it known that I, WADE H. HILLHOUSE, a citizen of the United States, residing at Lebanon, in the county of Cherokee and 5 State of Georgia, have invented certain new and useful Improvements in a Crossing Signal, of which the following is a specification.

This invention relates to a crossing signal 10 structure especially adapted to be used at intersections of a road or highway with a railway track for automatically displaying a signal as a train approaches the crossing, and it consists in the novel features herein- 15 after described and claimed.

An object of the invention is to provide a 20 structure of the character stated which is automatic in its operation and adapted to be actuated by an approaching train to dis- play the signal and to return the signal to its normal position after the train has made 25 the crossing.

With the above object in view, the structure includes a post which is mounted adjacent the intersection of a road and railway track and which carries at its upper end an arm which is disposed over the road. A bar is pivotally mounted upon the upper portion of the post and carries at its longer 30 end portion a pivoted signal member which is adapted to hang approximately in a vertical position when the arm is lowered and which is disposed by the said arm in a substantially horizontal position when the bar 35 is raised. The bar is fixed to a shaft which is journaled in the post and a ratchet wheel is mounted upon said shaft. A spring-pressed pawl engages the teeth of the ratchet wheel to hold the bar in its raised or lowered 40 position. A lever is fixed to the shaft and is operatively connected with a pivoted trip mechanism having an end portion disposed at the side of one of the rails of the track. A lever is pivoted upon the post and is engageable with the pawl to move the same out of engagement with the teeth of the ratchet wheel. A last mentioned lever is operatively connected with a trip mechanism having an end portion located adjacent the track rail. 45 One end of the lever which is mounted upon the shaft is connected by means of a cable with a trip mechanism having an end portion disposed adjacent the track rail, and the last mentioned trip mechanism is located at the opposite side of the roadway from the first mentioned trip mechanism.

In the accompanying drawing:—

Figure 1 is a side elevation of the crossing signal showing the relative positions of the parts when the bar is in an elevated position. 60

Figure 2 is a top plan view of the crossing signal.

Figure 3 is a fragmentary side elevation of the crossing signal showing the bar there- 65 of in lowered position.

Figure 4 is a perspective view of a signal member used in the signal structure.

Figure 5 is an enlarged fragmentary transverse sectional view of the signal structure cut on the line 5—5 of Figure 1. 70

Figure 6 is a diagrammatic view of an electric circuit, a signal lamp and circuit closer which may be used in conjunction with the signal structure. 75

As illustrated in the accompanying drawings, the roadway is indicated at 1 and the railway track at 2. The said roadway and track intersect each other at grade in a usual manner. The signal structure includes a post 3 which is erected adjacent the point of intersection between the road and track. A fixed arm 4 is carried at the upper end of the post 3 and is disposed above the intermediate portion of the road 1. A shaft 5 is journaled for rotation in the upper portion of the post 3 and a bar 6 is fixed to the said shaft. A spring 7 is connected at one end with the shorter end portion of the bar 6 and at its other end with the intermediate 80 portion of the post 3. Said spring 7 is under tension with a tendency to normally hold the longer end portion of the bar 6 toward the arm 4 as shown in Figure 1. A ratchet wheel 8 is fixed to the shaft 5 and a pawl 9 is pivoted upon the post 3. A spring 10 is connected at one end with the pawl 9 and at its other end with the post 3 and is under tension with a tendency to hold the engag- 85 ing end of the pawl 9 toward the teeth of the ratchet wheel 8. A lever 11 is fixed at a point between its ends to the shaft 5 and a wire or cable 12 is connected with the lower end of the lever 9. The intermediate portion of the wire or cable 12 is trained through the upper ends of supporting posts 13, a shaft 14 is journaled for turning move- 90 ment adjacent the track and is disposed transversely with relation to the rails there- of when at the side of the track. An arm 15 is fixed to the shaft 14 and one end of the cable or wire 12 is connected with said arm 95 100 105 110

15. An arm 16 is also fixed to the shaft 14 and is provided with a curved free end portion 17 which is disposed adjacent one of the rails of the track 2 and which carries a journaled roller 18.

A shoe 17' is carried by the pilot of the locomotive which moves on the track 2 or may be carried by any other piece of rolling stock. A signal member 18 is pivotally mounted at the free end of the bar 6. The member 18 is in the form of a plate having at its upper edge curls 19 which loosely surround the end portion of the bar 6. The signal member 18 is provided with a shank portion 20 which is located between the curls 19 and which is curved longitudinally. A lever 21 is pivoted upon the upper portion of the post 3 and when swung is adapted to engage the lower portion of the pawl 9. A wire or cable 22 is connected at its upper end with the outer end of the lever 21 and is connected at its lower end with an arm 23 mounted upon a shaft 24 which is disposed transversely of the rails of the track 2. Arms 25 are carried by the shaft 24 and are disposed adjacent the outer surfaces of the rails of the track 2. The arms 25 are similar in structure to the arms 16 hereinbefore described. The arms 16 and one of the arms 25 are located in the path of movement of the shoe 17' as the locomotive or car passes over the crossing or approaches the same. A shaft 26 is journaled for turning movement at the opposite side of the road 1 from the shafts 24 and 14 hereinbefore described. An arm 27 is carried by the shaft 26. A cable or wire 28 is connected at one end with the arm 27 and connected at its other end with the upper end of the lever 11. The intermediate portion of the wire or cable 28 is trained through the upper ends of supporting posts 19 and the said wire or cable 28 is trained through an eye 30 mounted upon the upper end of the arm 4.

Assuming that the parts are in the position as shown in Figure 1 of the drawings, and a train is approaching the crossing in the direction indicated by the arrow in the said figure. The shoe 17' strikes the upper end of the arm 16 and rides over the roller 18 whereby the free end portion of the arm 16 is depressed and the shaft 14 is turned, thus swinging the arm 15. This moves the wire or cable 12 longitudinally, whereby the lever 11 is swung and the shaft 5 is turned. This lowers the inner end of the bar 6 to the position shown in Figure 3 and the signal member 18 will swing from a substantially horizontal position as shown in Figure 1 to the vertical position as shown in Figure 3 and will be disposed above the intermediate portion of the road 1. Therefore, the traffic upon the road 1 which is approaching the crossing is warned of the approach of a train over the railway track. When the shaft 5 is

turned as above indicated, the wheel 8 is turned with it and the pawl 9 under the influence of the spring 10 engages the teeth of the wheel 8 and holds the bar 6 in a lowered position. When the shoe 17' strikes the arm 25 the shaft 24 is turned whereby the arm 23 is swung and the cable or wire 22 is moved longitudinally and the lever 21 is swung so that its lower end strikes the lower portion of the pawl 9 and swings the same against the tension of the spring 10 so that its upper end disengages the teeth of the ratchet wheel 8. The tension of the spring 7 then comes into play and the arm 6 is swung to the elevated position shown in Figure 1. In doing so the longitudinally curved stem 20 of the signal member 18 rides along the lower edge of the arm 4 and the said signal member is swung from the vertical position shown in Figure 3 to the substantially horizontal position as shown in Figure 1. Thus the signal is raised and lowered as the train passes over the crossing. Should the train be approaching the crossing in the direction opposite from that indicated by the arrow in Figure 1, the shoe 17' will strike the arm mounted upon the shaft 26 and the cable 28 will be moved longitudinally whereby the lever 11 is swung and the bar 6 is moved from an elevated to a lowered position. After the train passes over the crossing the shoe 17' strikes one of the arms 25 upon the shaft 24 and thus the cable 22 is moved longitudinally as hereinbefore described and the engaging end of the pawl 9 is moved out of engagement with the teeth whereby the bar 6 may swing from a lowered to an elevated position as hereinbefore described.

In order that the movement of the bar 6 may be observed at night, an electrically illuminated signal is mounted thereon. The said signal includes a lamp 31 connected in open circuit with a battery 32 which is carried by the bar 6. The circuit wires are indicated at 33 and the circuit over the said wires is normally opened. The wires connect with spaced terminals 34 which are also carried by the bar 6. A stem 35 is movably mounted between the terminals 34 and carries a head 36 which may engage both of the said terminals and bridge the space between thus completing the circuit from the battery 32 to the lamp 31. A spring 37 is interposed between a fixed part mounted upon the arm 6 and bears against a collar 38 which is carried by the stem 35. The spring 37 is under tension with a tendency to normally hold the head 36 in contact with the terminals 34 and the upper end of the stem 35 projected above the upper edge of the bar 6. Therefore when the bar 6 is moved up against the arm 4 as shown in Figure 5 of the drawings, the head 36 is spaced from the terminals 34 and the electric circuit from the generator 32 to the lamp 31 is interrupted.

- ed. As soon as the bar 36 swings in a downward direction, the tension of the spring 37 comes into play whereby the head 36 is moved in contact with the terminals 34 thus completing the circuit from the battery 32 to the lamp 31. Therefore the lamp 31 is illuminated and a visible signal is exhibited at night to indicate that the arm is lowered and that a train is approaching.
- 10 It will be noted that the within described signal is capable of extensive use and is at the same time inexpensive, simple in construction, economic to operate and easy to regulate.
- 15 As many changes could be made in carrying out the construction and many apparently widely different embodiments of the invention could be made without departing from the scope thereof, it is intended that all matter contained in this description or shown in the drawing should be interpreted as illustrative and not in a limiting sense. It is also to be understood that the language used in the following claims is intended to cover all of the generic and specific features of the invention herein described and all statements of the scope of the invention, which, as a matter of language, might be said to fall therebetween.
- 20
- 25
- 30 Having thus described the invention, what I claim is:—
1. A crossing signal comprising a post having an angularly disposed arm, a shaft journaled therein, a bar fixed to the shaft, a trip operated mechanism for turning the
- 25
- 30
- 35
- shaft, means for holding the shaft when turned, a trip operated mechanism for releasing the shaft, means for returning the shaft and a signal member carried by the bar and engageable with the arm and adapted to be swung from a horizontal to a vertical position as the arm is raised and lowered.
2. A crossing signal comprising a post, an arm carried by the post, a bar pivoted upon the post, means for raising and lowering the bars, a signal member pivoted upon the bar and having a longitudinally curved shank portion adapted to engage the lower edge of the arm whereby the said signal member is swung from a horizontal to a vertical position as the bar is raised and lowered.
3. A crossing signal comprising a post having an angularly disposed arm, a bar pivoted thereon, means for swinging the bar, a signal member pivotally mounted upon the bar and having a longitudinally curved shank adapted to engage the lower edge of the arm whereby the signal member is swung from a horizontal to a vertical position as the bar is raised and lowered, an electric illuminated signal carried by the bar and means carried by the bar for closing the circuit to the illuminated signal when the bar is lowered the parts being so arranged that the circuit closer will encounter the arm when the bar is raised and interrupt the circuit to the electric signal.

In testimony whereof I affix my signature.
WADE H. HILLHOUSE.
